(57) **CLAIM**

The ornamental design for single refrigerator drawer, as shown and described.

DESCRIPTION

FIG. 1 is a front perspective view of a single refrigerator drawer showing our new design;

FIG. 2 is a front elevational view thereof;

FIG. 3 is a right side elevational view with the left side being a mirror image thereof; and,

FIG. 4 is a top plan view thereof.

The broken lines shown in FIGS. 1, 2, and 3 are for illustrative purpose only and forms no part of the claimed design.
